UNITED STATES PATENT OFFICE.

ABRAM E. SMITH, OF HUGUENOT PARK, NEW YORK, ASSIGNOR TO UNION TANK CAR COMPANY, OF JERSEY CITY, NEW JERSEY, A CORPORATION OF NEW JERSEY.

RAILROAD CAR.

Application filed June 4, 1925. Serial No. 34,760.

My present invention relates to railroad cars, and particularly tank cars of the well-known type, and has for its object the improvement and cheapening of the construction of the under-frame of such cars.

My invention will be best understood from the following description and the annexed drawings, in which Fig. 1 is a side elevation, more or less diagrammatic, of a tank car to which my invention has been applied; Fig. 2 is a plan view of the car shown in Fig. 1; Fig. 3 is a plan view of a portion of the under-frame of the car shown in Figs. 1 and 2 and embodying my invention; Fig. 4 is a side view of the arrangement shown in Fig. 3 with a portion thereof broken away along its longitudinal center line; Fig. 5 is a section of Fig. 3 on line 5—5; Fig. 6 is a section on an enlarged scale on the line 6—6 of Fig. 3, and Fig. 7 is a section on the line 7—7 of Fig. 3.

Like reference characters indicate like parts in the several views.

In the illustrative embodiment of my invention shown in the drawings, the tank car has the usual tank 10 supported on trucks at either end, and is, of course, provided with the usual coupler and draft gear, but since these arrangements are no part of my present invention, description thereof will be unnecessary to those skilled in the art.

The car is provided with a center sill 11 which is tubular in form. At each end of this tubular center sill is a casting to which the center sill is rigidly attached, in a manner to be described more in detail herein-after, this casting being formed to constitute a body bolster having outboard projections 12, a draft sill projection 13 and a center sill projection 14. The outboard projections 12 are provided with slabbing brackets 15, on which is carried the slabbing 16 for supporting the tank 10. The draft sill projection 13 is provided with a space 17 to receive the draft gear and coupler shank, the draft gear being supported on a plate 18. The end casting is also provided with a king pin recess 19 and a cover plate 20'. A frame in the usual manner may be extended out from the projections 12 and 13, as shown best in Fig. 3.

The specific form of the end casting will, of course, be changed to accord with the particular form of draft gear and coupler, and the particular form of car body support with which my invention is used, and it will be

understood that the arrangement shown and described is merely to indicate the general character of the construction.

The projection 14 on the end casting, as shown best in Fig. 4, is preferably made cylindrical and is fitted into the interior of the end of the tube 11 with a shoulder 14' between the projection 14 and the remainder of the casting, and with the end of the tube 11 fitting snugly against this shoulder. Rivets 65 or any other suitable fastening means may be used to connect the projection 14 with the tube 11.

With the arrangement so far described, it will be obvious that the two end body bolsters are connected by a tubular strut, which is not only cheaper than the usual built up center sill, but by the arrangement that I have shown is so connected to the body bolsters that the thrust from one to the other, 75 due to shock, is transmitted directly to the tube itself through the shoulders on the end casting, and the rivets connecting the two members are not called on to stand any of this compression shock. The rivets, of course, furnish ample connection for the 80 pulling strains transmitted through the member 11.

In the illustrative arrangement, an anchor is provided to connect the tank to the center sill, and in the form shown in the drawings, such anchor comprises what is, in effect, a split casting having a cylindrical portion surrounding the tubular center sill, and having a pad riveted to the tank 10. This split casting is really made in two parts which, for purposes of convenience, I have designated as the upper casting and the lower casting. The upper casting, in the form shown, has a pad 20 riveted to the tank 10, and a hollow downwardly projecting portion 21, the casting being provided with a pair of discharge ducts or nozzles 22, one on either side of the casting. The upper casting is also provided with projecting pads 23—23. 95

The lower portion of the split member has a cylinder portion 24 preferably riveted to the tubular sill 11, and is also provided with projecting pads 25—25. The parts are so dimensioned that preferably there is a space 100 between the pads 23 and 25, so that when the bolts 26 are passed through these pads, the cylinder portion of the upper casting will be drawn down tightly against the tubular sill 11. Preferably, the cylindrical 110

portions of the upper and lower castings will be provided with separated contact seats instead of a continuous bearing surface.

The nozzles 22 are threaded and provided with caps 27. The tank 10 is provided with a discharge opening 28 within the area of the hollow portion 21 of the upper casting, and this discharge opening is provided with any suitable valve operable from the top of the tank, such, for instance, as is shown in my prior Patent No. 1,136,375, patented April 20, 1915, such a valve being indicated at 29 in Fig. 6. It will be observed that a recess 21 in the top of the pad 20 of the hollow portion 21 forms a sump into which opens the discharge opening 28. From this sump, the contents of the car may be completely discharged through the dome of the tank, by means of a pipe indicated at 30 passing through an opening 31 in the top of the dome 32 into this sump 21.

The anchor, which I have described, not only serves to hold the tank securely to the tubular member 11, but enables the removal of the tank from the under-frame without the necessity of cutting any rivets if bolts 26 are used, or if the pads 23 and 25 are riveted together, then merely by cutting such rivets. In this way, the riveted connection between the tank and the upper casting is not disturbed in such removal, and since the rivet connections between the tank and the anchor must be kept liquid-tight, it is obvious that my arrangement avoids the disturbance of these liquid-tight connections. By having the discharge nozzles 22 extending from either side, the contents of the tank may be discharged in either direction by merely removing cap 27 from the appropriate nozzle 22.

While preferably I make the end casting with integral projections, as illustrated, it will be obvious that, if desired, such projections may be made of rolled sections and attached to the anchor casting to which the tubular member 11 is connected.

It will also be understood that the arrangement which I have shown is merely illustrative and that the embodiment of my invention may be widely varied.

I claim:

1. A railroad tank car having a tubular center sill, and an anchor casting for the tank comprising a member riveted to the tank and surrounding and clamped to the center sill.

2. A railroad tank car having a tubular center sill, and an anchor casting for the tank comprising two castings, one of which is riveted to the tank, the two castings surrounding said center sill and being clamped thereto.

3. A railroad tank car having a center sill, a casting secured to the tank and to said center sill, said casting being provided with

a sump communicating with said tank whereby the fluid in said tank may be drained from said sump.

4. A railroad tank car having a center sill, a casting secured to the tank and the said center sill, said casting being provided with a sump communicating with said tank, said casting being provided with outlet nozzles extending either side of said center sill and communicating with said sump.

5. A railroad tank car having a tubular center sill, an end casting at either end of the center sill and connected rigidly thereto, each of said castings having recesses for the king pin of the truck bolster and for the draft gear, and an anchor casting for the tank comprising a member riveted to the tank and surrounding and clamping to the tubular sill.

6. A railroad tank car having a tubular center sill, an end casting at either end of the center sill and connected rigidly thereto, each of said castings having recesses for the king pin of the truck bolster and for the draft gear, and an anchor casting for the tank comprising an upper casting riveted to the tank, and having a cylindrical portion partially surrounding and resting on the center sill and a lower casting having a cylindrical portion partially surrounding the center sill below the cylindrical portion of the upper casting, and bolts to connect the two castings.

7. A railroad tank car having a tubular center sill, an end casting at either end of the center sill and connected rigidly thereto, each of said castings having recesses for the king pin of the truck bolster and for the draft gear and an anchor casting for the tank comprising an upper casting riveted to the tank, and having a cylindrical portion partially surrounding and resting on the center sill and a lower casting having a cylindrical portion partially surrounding the center sill below the cylindrical portion of the upper casting, and bolts to connect the two castings, the cylindrical portion of the lower casting being riveted to the tubular sill and said castings being arranged so that the bolts will draw the cylindrical portion of the upper casting into clamping engagement with the tubular sill.

8. A railroad car having a tubular center sill, an end casting at either end of the center sill and connected rigidly thereto, each of said castings having recesses for the king pin of the truck bolster and for the draft gear, and an anchor casting for the tank comprising an upper casting riveted to the tank, and having a cylindrical portion partially surrounding and resting on the center sill and a lower casting having a cylindrical portion partially surrounding the center sill below the cylindrical portion of the upper casting, and bolts to connect the two castings,

said bolts being the only connection between said upper casting and the sill.

9. A railroad tank car having a tubular center sill, an end casting at either end of the center sill and connected rigidly thereto, each of said castings having recesses for the king pin of the truck bolster and for the draft gear, and an anchor casting for the tank comprising an upper casting riveted to the tank, and having a cylindrical portion partially surrounding and resting on the center sill and a lower casting having a cylindrical portion partially surrounding the center sill below the cylindrical portion of the upper casting, and bolts to connect the two castings, said tank having a valve-controlled discharge opening above said upper casting and said upper casting having a discharge duct opening at the side of said casting, whereby the contents of the tank may be discharged when the discharge opening valve is opened.

10. A railroad tank car having a tubular center sill, an end casting at either end of the center sill and connected rigidly thereto, each of said castings having recesses for the king pin of the truck bolster and for the draft gear, and an anchor casting for the tank comprising an upper casting riveted to the tank, and having a cylindrical portion 25 partially surrounding and resting on the center sill and a lower casting having a cylindrical portion partially surrounding the center sill below the cylindrical portion of the upper casting, and bolts to connect the 30 two castings, said tank having a valve-controlled discharge opening above said upper casting and said upper casting having a discharge duct at each side of the casting and connected to said discharge opening, 35 and a removable closure for each discharge duct.

ABRAM E. SMITH.
